CARBURETING RING STRUCTURE FOR
WALL FLAME BURNERSMilton A. Powers, Detroit, Mich., assignor, by
mesne assignments, to The Timken-Detroit
Axle Company, a corporation of Ohio

Application October 6, 1934, Serial No. 747,220

9 Claims. (Cl. 158—4)

This invention relates to apparatus for burning liquid fuel in accordance with what has some to be known recently as the "wall flame" principle.

5 This application is a continuation-in-part of my co-pending application, Serial Number 729,928, filed June 9, 1934 for Fuel burning methods and apparatus; and is related to my earlier application, Serial Number 620,373, filed July 10 1st, 1932 for Ignition and combustion rings for liquid fuel burners.

15 The most desirable type of apparatus for burning oil on the wall flame principle consists, as disclosed in said co-pending application, Serial Number 729,928, of a substantially horizontal hearth closing in the bottom of the combustion chamber, a central rotary head for distributing oil and air in distinctly separate layers toward the periphery of the hearth and a metal vaporizing and carbureting ring structure located adjacent the hearth periphery between the distributing head and the wall of the combustion chamber. A satisfactory ring structure for use in this combination is disclosed in my above-mentioned application, Serial Number 620,373, 20 wherein a plurality of metal segments are mounted end to end upon the hearth to form the ring. In my other above-mentioned application, Serial Number 729,928, it has been proposed to 25 make up such a ring structure as a single piece having a continuous or unbroken surface substantially throughout its length by forming it as an endless structure or as a split ring having its ends in abutment.

30 35 It is a primary object of the present invention to devise a new and improved, and particularly a simplified form of metal carbureting and vaporizing ring structure of the general type just mentioned, having continuity substantially throughout its length.

40 It is an object of my invention to provide a light metallic combustion wall of special design for a liquid fuel burner of the wall flame type, and especially to devise and so arrange a metal vaporizing wall as to promote maximum efficiency both in normal operation and when starting and stopping the burner apparatus.

45 50 It is a further major object of this invention to provide a simple channeled metal ring structure of endless formation in effect, whereby continuity is obtained substantially throughout its length. More specifically, it is an object to devise a channeled metal ring structure comprising an outer impenetrable high wall for fuel impingement and an inner low wall spaced from the

high wall to form an ignition gutter or channel therebetween.

5 It is another object of the present invention to provide, adjacent the hearth periphery of a wall flame type burner, a chrome-steel ring formed of a simple upright horizontally curved band.

10 It is also an object of this invention to devise, for use adjacent the hearth periphery of a rotary wall flame oil burner, a metal vaporizing and carbureting structure that is simple to manufacture, easy to install and efficient in operation.

15 It is a further major object of my invention to devise new and useful means for mounting a carbureting structure upon the hearth of a combustion chamber between the fuel distributing means and the surface to be heated. In this connection it is a specific object of my invention to devise a mounting means especially adapted for use on ceramic hearths; and it is 20 another object to devise a special mounting means for use on metallic hearths.

25 It is a further important object of this invention to devise new and improved ignition means, and particularly, ignition means designed for use in connection with a metal fuel vaporizing wall.

30 The foregoing and further objects of the invention will fully appear upon a study of the following detailed description when taken in conjunction with the accompanying drawings and 35 the appended claims.

Referring now to the drawings wherein like numerals are employed to designate like parts wherever they occur;

Figure 1 is a vertical sectional view taken substantially centrally through the combustion chamber and associated parts of one preferred form of apparatus embodying my invention.

Figure 2 is a detailed view in perspective of one of the ignition devices of Figure 1 and the 40 mounting means used in connection therewith.

Figure 3 is a view in perspective of one of the positioning assemblies utilized in Figure 1 to hold the ring structure upon the hearth.

Figure 4 is a fragmentary sectional view corresponding in general with Figure 1, but showing a modified hearth construction for association with the vaporizing and carbureting ring structure.

Figure 5 is a detailed view in section of one of 50 the elements utilized in Figure 4 to secure the metal rings to the metal hearth.

The preferred burner system for incorporation in the invention consists of a distributor unit centrally located in a hearth, and which cen-

trifugally throws oil and air in separate layers to the outer periphery of the hearth, with the combustion ring structure of this invention located adjacent said outer periphery; means for 5 electrically igniting the oil, which is mixed with the air at the combustion ring; and grills for spreading the flame obtained. There are two forms of this general apparatus for embodiment of the invention. The first comprises a molded 10 or ceramic hearth for use in boilers or furnaces originally designed for burning coal or similar fuel; and the second comprises a metal hearth for use in furnaces which are originally designed for burning oil.

15 The furnace of Figure 1 is of the converted coal burning type and comprises a boiler or water heater B, supported in the usual manner above the ash pit P. The latter also supports a hearth structure H which is built thereupon, and 20 centrally of this hearth structure there is provided a supporting stand S carrying a rotary fuel and air distributing mechanism D driven by an electric motor M. Mounted upon the hearth adjacent to, but spaced inwardly from the 25 periphery thereof, is a fuel vaporizing and carbureting ring structure R which is designed to support a plurality of flame controlling grills G. A pair of igniter assemblies I are disposed for cooperation with the ring structure and receive 30 electrical current through a transformer T. The transformer and the electric motor M are connected to a control stand C so as to be conveniently placed under manual and automatic control in the usual manner. Liquid fuel such as oil is 35 supplied to the distributing mechanism by a line L which likewise is connected to the control stand so as to be governed in the usual manner by mechanism associated with the latter.

40 Of the major parts of the apparatus above described, only the ring structure R is claimed herein to be new, and as the present invention resides entirely therein and in the mounting means therefor, but little attention need be devoted to the structural details of the conventional parts of the apparatus.

45 The hearth structure H comprises a metal plate assembly 7 with ceramic material 8 of a refractory nature molded thereupon and around the upper part of the supporting stand S to completely close the bottom of the combustion chamber and to provide a substantially horizontal upper surface. The rotary distributing head D is preferably constructed exactly as disclosed in my afore-mentioned co-pending application, Serial Number 729,928 and made in substantially 50 the same form as that shown in my Patent No. 1,888,693. The chief requisites are that it receive oil and air internally of the supporting stand S and discharge them without admixture 55 and in distinctly separate layers outwardly toward the periphery of the hearth. For this purpose the rotary head has a plurality of fan blades 9 for projecting air in a concentrated layer directly across the hearth surface, and one or more flinger tubes 10 for throwing oil outwardly in the form of relatively large unatomized droplets directly above the path of air flow.

60 The vaporizing and carbureting ring structure R comprises a pair of cylindrical upright bands 70 12 and 13 concentrically arranged adjacent the igniters near the outer periphery of the hearth. The metal band 12 is of materially greater diameter than that of the band 13 and it is of such height that when standing upon the hearth its upper edge will preferably be at a higher level

than the discharge ends of the flinger tubes 10. In this manner the upper portion of the band 12 will be disposed in the path of the projected liquid fuel and it is for this reason that this particular band is called a vaporizing ring. The 5 band 13 is less than one-half as high as the band 12 and accordingly will not interfere with or intercept the fuel that is projected toward the upper portion of the band 12. The band 13 does, however, intercept the air that is supplied outwardly over the hearth to prevent the air blast from sweeping directly into the annular channel that is formed between the two bands. It causes some of the air to eddy downwardly into the channel, but directs the bulk of the projected 10 blast toward the upper edge of the higher ring 12 to carburete the fuel that is vaporized by the latter and it is for this reason that the band 13 is called an air-deflecting ring.

15 The carbureting ring construction is maintained in the position illustrated in Figure 1 by a plurality of mounting means that are best seen in Figures 2 and 3. With particular reference to Figure 3, a flat strip of metal 14, designed to be molded in the hearth and have its horizontal portion slightly below the top surface of the hearth, with its longitudinal axis arranged radially with respect to the hearth and the two rings, has a pair of legs 15 struck downwardly from its ends for anchoring embedment in the 20 molded portion 8 of the hearth. A substantially U-shaped holding and positioning member 16 for the two rings is seated upon the mid-portion of the strip 14. This U-shaped member has a relatively long upstanding leg 17 designed to cooperate with ring 12, and a relatively short upstanding leg 18 designed to cooperate with the ring 13. This U-shaped member is anchored upon the strip 14 by a spot welding or like operation. A plurality of tabs 19 are struck upwardly from the sides of strip 14 so that the tabs engage the edges of the base of the U-shaped member as shown in Figure 3. The tabs of each pair, in the longitudinal direction of the strip 14, are so spaced that their outer edges will abut against 25 those surfaces of the two rings which face toward each other and thus prevent radial movement of the lower edges of the rings. Tabs 19 are intended to remain upright, but if desired they may be bent down against the upper surface of the U-shaped member. Member 16 preferably lies slightly below or flush with the hearth surface so that the lower edges of the rings may be slightly embedded in, or fit snugly directly 30 upon the hearth surface, with the result that the channel formed between the two rings will thus be effectively closed at its bottom. The upper ends of the legs 17 and 18 of the U-shaped member 16 have integral clamping extensions, 35 20 and 22 respectively, that project above the upper edges of the two rings and that are designed to be bent downwardly into engagement with the inner ring walls, as illustrated in Figure 1. Although the rings may be welded in place, I preferably frictionally hold them in place by means of clamping extensions 20 and 22, so that the rings may freely expand and contract 40 in response to temperature changes without undergoing distortion. There are preferably a plurality of these positioning and holding assemblies located about the periphery of the ring structure, but at two diametrically opposite points where the two igniter structures I are located, the positioning means will preferably 45 50 55 60 65 70 75

take a slightly different form, as illustrated in Figure 2.

With further reference to Figure 2 the flat strip 140 corresponding with the strip 14 of Figure 3 is shortened at its inner end and has in lieu of an integral anchoring leg 15, a depending bracket 23 welded to the bottom of each strip carrying an integral cylindrical strap 24 that is designed to be nested into or embedded in the upper surface of the molded hearth portion 8 (see Figure 1). This strap 24 encircles a cup-shaped insulator 25 which projects downwardly through the hearth and which centrally carries an inner insulating member 26. The member 26 is in the form of a sleeve through which passes a metal conductor 27 that is connected at its lower end with the transformer T. The upper end of the conductor 27 has an electrode tip 28 and is so bent as to have a large air gap between it and all parts of the ring structure except where the tip 28 is brought into proximity to the vaporizing ring 12.

The flaming arc for ignition purposes may be produced directly between the electrode tip 28 and the ring 12, but preferably the special arrangement illustrated in Figure 2 is utilized. This arrangement comprises an upstanding bracket 29 welded to the upper surface of the base portion of the U-shaped member 16 and carrying at its upper end an integral firing plate 30. Bracket 29 is spaced from the leg 11 sufficiently to afford snug reception of the ring 12 between these two members and thus the bracket 29 takes the place of one set of the tabs 19 of Figure 3. The function and advantages of this firing plate will be set forth later.

The flame controlling grills G are not essential to operation of the burner apparatus, but it is preferable to utilize them for the purpose of holding the flame down and concentrating heat at the lower part of the boiler leg. The grill-work may be formed of individual segments, each comprising a perforated metal plate 32 constructed in the manner illustrated in the pending application of J. A. Wilson, Serial Number 682,374, and with substantially U-shaped brackets 33 welded to the bottoms of the plates and designed to be clipped upon the upper portion of the ring 12. The perforated plates 32 are preferably so positioned as to overhang the annular gutter formed between the two rings 12 and 13, and to partially overhang the annular space that is formed between the vaporizing ring 12 and the inner wall of the boiler.

The ring holders and grills are all formed of metal and the metal used, particularly that for the ring, must have high thermal conductivity and also possess high resistance to deformation or destruction by heat. A satisfactory metal for this purpose is a steel embodying 16 to 18% chromium and a very low carbon content. Some nickel, as high as 8%, may be added. Due to difficulties encountered in shaping such a metal into complex structural formation without producing a structure that is weak or likely to cause later trouble, the illustrated simple construction is very desirable as it comprises merely two simple cylindrical bands and the other metal parts are of simple but effective construction. Each ring may be formed in an endless piece, or may be bent or rolled into the desired shape from a single straight strip of material, in which event its ends will be held close together during use. The ends of such a strip may be welded together, if desired, to obtain complete circular continuity of surface.

Assuming that the furnace of Figure 1 is cold, upon starting the motor the distributing head D will be rotated at about 1750 R. P. M. and oil will be thrown substantially radially outwardly by finger tubes 10 in a trajectory that intersects the upper portion of the vaporizing ring 12. Simultaneously, a concentrated blast of air will be projected radially by the blades 9 along the hearth and when this blast reaches the ring 13 it will be deflected upwardly toward the top of the ring 12 while, as aforesigned, some of the air will eddy into the groove formed between the two rings. As the ring 12 is cold, it will not produce any vaporization at this time. The oil impinging thereon will be shattered into smaller particles and part of it will flow downwardly into the bottom of the ignition gutter or groove formed between the two rings. During this starting period an ignition current is passing from the transformer to one of the igniters, thence through the band or ring 12 and thence through the other igniter for return to the transformer. An intense flaming arc is obtained between each terminal 28 and the corresponding firing plate 30, and these arcs will cause a flame to be produced above the surface of the oil collected in the gutter. The use of the firing plate 30, rather than allowing the spark to fire or arc directly against ring 12 insures that the gap will have a fixed clearance at all times. If the arc fired against ring 20, the gap would have to be adjusted at the time of installation. With the integral gap assembly no adjustment is required.

The thin metal rings and grills, having high conductivity without excessive heat capacity, rise in temperature very rapidly, and therefore in only a short time they are at normal operating temperature, permitting the ignition to be cut off. Under this normal heat, the projected oil is vaporized almost instantly as it spatters against the vaporizing ring 12 and at the top of the latter becomes perfectly carbureted with the air that is passed over the top of ring 13. Any oil that may on rare occasions, as the result of delayed ignition accumulate in the gutter, is rapidly consumed and this is also true of any oil that may get behind the vaporizing ring, as the latter is spaced sufficiently inwardly from the boiler wall to permit a part of the flame to wipe downwardly into the space adjacent the bottom of the boiler leg. As previously stated the flame is held down and concentrated by the flame controlling and spreading grills G.

Figure 4 is incorporated to show my invention embodied in association with a boiler B2 and a base P2 that are specially designed for cooperation with a metallic hearth to burn liquid fuel. In this form the hearth structure H2 comprises a metal supporting plate 34 which is bolted to the upper part of the base at its periphery and designed to support the motor and distributor mechanism at its apertured center; a sheet of insulating material 35 arranged upon the plate 34; several U-shaped brackets 36 arranged upon the sheet of insulating material and a metal pan 37 or hearth proper which is supported by the brackets 36. This metal pan has a close fit at its apertured center with the head support S2 and is turned up at its periphery so that it will prevent the overflow of any small accumulations of oil. In like manner it has a close turned up fit with the ignition device I2 and any other elements that may project through the hearth.

In the form just described, the vaporizing and deflecting rings, 120 and 130 respectively, which

are identically the same, both in structure and function as rings 12 and 13, rest in continuous circular contact with the hearth pan 37, and are maintained in position with respect thereto by a series of metal angle members 38 each of which has a horizontal wing 39 adapted to be welded to the hearth pan and an upright wing 40 adapted to be welded to the ring. One of these members is illustrated in detail in Figure 5.

10 In the form of invention just described, the flaming arc from the ignition device passes directly from the electrode tip 28 to the vaporizing ring 120. However, a firing plate may be utilized if desired, similar to that shown in Figure 2. In 15 all other respects the operation is precisely the same as that set forth for the apparatus of Figure 1. In some installations it may be desirable to utilize a special fan for use with the all metal hearth structure; and such a fan, for delivering 20 a very thin concentrated stream of air along the hearth surface is disclosed in my afore-mentioned application, Serial Number 729,928.

Although I have illustrated rings 12 and 13 as being formed of strips bent into cylindrical form, 25 so as to conform to the shape of the combustion chamber of the particular boiler shown which is of cylindrical form in horizontal section, it is to be understood that where the boiler or furnace is rectangular or oval in section, the rings may 30 be bent to take the form of straight portions merging into curved portions or may be of oval shape so as to generally conform to the combustion chamber. It is to be moreover understood that although the rings have each been disclosed 35 as being constructed of a single piece of metal, they may, if desired, be constructed in several pieces, overlapped in the region of the connectors, so that they may slide back and forth in the frictional grip of the connectors in response to temperature changes, and the appended claims are 40 intended to embrace my invention when it assumes this form.

Various other types of ignition assemblies and 45 circuits may be utilized. For instance, that disclosed in prior Patent No. 1,890,862, and in my co-pending application, Serial Number 731,562, filed June 20th, 1934, may be readily incorporated in the vaporizing and carbureting ring structure of the present invention.

50 The invention may be embodied in other specific forms without departing from the spirit or essential characteristics thereof. The present embodiments are therefore to be considered in all respects as illustrative and not restrictive, the scope 55 of the invention being indicated by the appended claims rather than by the foregoing description, and all changes which come within the meaning and range of equivalency of the claims are therefore intended to be embraced therein.

60 What is claimed and desired to be secured by United States Letters Patent is:

1. In a liquid fuel burning apparatus having a combustion chamber provided with a hearth and an upright wall, and means for projecting fuel 65 toward said wall, an upright strip of refractory material disposed above the hearth to intersect the path of the projected fuel, and means for positioning said strip relative to the hearth, said means comprising a device secured to the hearth 70 and having an upward extension providing a clip for reception of the upper edge of said strip.

2. In a liquid fuel burning apparatus having a combustion chamber provided with a hearth and an upright wall, and means for projecting fuel 75 toward said wall, an upright strip of refractory

material disposed above the hearth to intersect the path of the projected fuel, and means mounted on the hearth for positioning said strip relative to the hearth, said means comprising a horizontal metal member having a leg extending upwardly for engagement with that side of said strip which is adjacent the hearth wall, and another integral leg providing a metal firing plate extending upwardly into engagement with the other side of the strip, and an electrode disposed adjacent said firing plate on that side of the latter which faces the fuel projecting means.

3. In a liquid fuel burning apparatus having a combustion chamber provided with a hearth and an upright wall, and means for projecting fuel toward said wall, an upright strip of refractory material disposed above the hearth to intersect the path of the projected fuel, and means for positioning said strip relative to the hearth, said means comprising a device secured to the hearth and provided with a leg extending upwardly for engagement with one side of said strip, and said device further having means spaced from said leg a distance substantially equal to the thickness 20 of the strip and designed to engage the other side 25 of the strip.

4. In a liquid fuel burning apparatus having a combustion chamber provided with a hearth and an upright wall, and means for projecting fuel and air toward said wall, an upright structure comprising a pair of concentrically spaced annular rings disposed above the hearth in the general path of fuel and air projection, and means for securing said structure to said hearth, said means comprising a substantially U-shaped member having a horizontal part attached to the hearth and a pair of rigid legs extending upwardly from said horizontal part in close association with the respective rings, the upper end of each leg being shaped to grip the upper edge of a 40 corresponding one of said rings.

5. In the combination defined in claim 4, said horizontal part being attached to the hearth by a plate that is directly secured to the hearth and that has tabs struck upwardly therefrom and 45 bent into engagement with the upper surface of said horizontal part in proximity to the lower edges of said rings.

6. In a device of the character described adapted to be mounted as an assembled unit in a combustion chamber, a pair of upright refractory strips spaced apart laterally substantially in parallelism; a substantially U-shaped member having a bottom engaging corresponding edges of the strips and a pair of legs each engaging a certain side wall of one of the strips; and a substantially flat member engaging the bottom of the U-shaped member on that side thereof which is opposite the strips, said flat member having elements struck upwardly therefrom in close proximity to the strips so that the struck elements cooperate with said legs to maintain the strips in properly spaced relationship.

7. In the device defined in claim 6, said struck elements being bent over the bottom of said U-shaped member, and the upper ends of the latter being bent over the upper edges of the strips, whereby said strips are held against vertical separation relative to one another.

8. In a liquid fuel burning apparatus having a combustion chamber provided with a hearth and having an upright wall, and means for projecting fuel and air toward said wall, an upright structure comprising a pair of refractory strips spaced apart laterally and disposed above the hearth in 75

the general path of fuel and air projection, and means for mounting said structure on said hearth, said means comprising a substantially U-shaped member having a horizontal part engaging the lower edges of the strips and a pair of integral legs extending upwardly adjacent the respective strips, the upper end of each leg being shaped to receive and confine a portion of the upper edge of the corresponding strip.

- 5 10. In a liquid fuel burning apparatus, in combination with a combustion chamber having a hearth and an upright wall, with the hearth closing the bottom of said chamber in the vicinity of said wall, fuel distributing means for projecting a stream of liquid fuel above the hearth and toward said wall, means for projecting an air blast over the hearth below the fuel stream toward said wall, a thin cylindrically curved strip of metal set

upright on said hearth in the path of fuel projection and spaced materially from said combustion chamber wall in the direction of said projecting means, and a similar strip of metal spaced from the first mentioned strip between the latter and the projecting means, said strips being sealed by the hearth and thereby forming a vertical channel between them that is closed at its bottom by the hearth, said second-named strip of metal being narrower than said first-named strip of metal 10 for deflecting said air blast outwardly and upwardly adjacent the upper edge of said first-named strip of metal, the latter being formed of comparatively thin sheet metal that has good heat conductivity but high resistance to destruction by heat. 15

MILTON A. POWERS.
